UNITED STATES PATENT OFFICE.

HEINRICH CHRISTIAAN FERRON, OF AMSTERDAM, NETHERLANDS.

METALLIC ROOFING AND THE LIKE.

1,061,231.

Specification of Letters Patent.

Patented May 6, 1913.

Application filed June 29, 1912. Serial No. 706,735.

To all whom it may concern:

Be it known that I, HEINRICH CHRISTIAAN FERRON, a subject of the Queen of the Netherlands, residing at Prinsengracht 911, Amsterdam, in the Kingdom of the Netherlands, have invented certain new and useful Improvements in Metallic Roofing and the Like, of which the following is a specification.

- 10 This invention relates to nailless metallic roofings and the like of the kind in which metallic plates are attached by means of bent tongues integral therewith to allotted one-piece metallic purlins.
- 15 In my United States Letters Patent No. 780,946 there is described a roofing of the kind referred to, and in my United States Letters Patent No. 935,479 there is described a slotted one-piece metallic purlin for use 20 in such roofings.

The present invention has for its object to overcome certain of the disadvantages possessed by these previous arrangements and to this end it provides an improved construction of purlin and also of plate or tile whereby a stronger and more economical structure results, which is weatherproof and which is easy to repair.

According to the invention the roofing or 30 the like comprises one-piece slotted metallic purlins bent in such a way as to receive and accommodate the upper ends of metallic roofing plates, each of which plates is provided along its upper edge with an up- 35 standing transverse flange or weather strip from which project retaining tongues adapted to take into the slots in said purlins.

The purlin, which is adapted to be secured to the rafters, is formed from a single 40 strip of metal bent upon itself with a narrow distance piece separating the two overlying walls; equidistant slots being pierced along the line of junction of the upper edge of said distance piece with the upper overlying wall. The height of the distance piece is just sufficient to permit of the insertion of the upper edge of the metallic plate into the channel formed by the bent strip.

50 The metallic plate or tile, which may for example be rectangular in shape, is formed with a corrugation along each side edge and with an upstanding flange along the upper edge of the same height as the corrugations. 55 Integral with this flange are one or more, preferably two, projecting tongues set apart

a distance corresponding to that separating the aforesaid slots in the purlin. The lower edge of each plate or tile is also provided with an extension or tongue which is adapted to be bent inward to engage the next purlin below that with which the tongues at the upper edge of the plate engage. The purlins and plates may be applied either to roofs or to walls of buildings.

60 The invention is illustrated in the accompanying drawings in which—

Figure 1 shows a "blank" purlin after having been stamped out and before having been bent to shape. Fig. 2 is a perspective front view of the same purlin after having been bent to shape. Fig. 3 is a section on line A. A. Fig. 2. Fig. 4 is a perspective view of one of the metallic plates or tiles. Fig. 5 is a front elevation of a portion of 75 roofing constructed of the purlins and tiles of this invention, and Fig. 6 is a section on line B. B. Fig. 5.

Referring to Figs. 1, 2 and 3, each purlin is composed of a long narrow strip of sheet 80 iron, sheet steel or other suitable metal, which when in "blank" form is stamped along one edge at suitable distances apart with apertures 1 and along the opposite edge with notches 2 disposed opposite to said 85 apertures 1. At the same time the strip has stamped out of it a row of slots 3 which are located in alinement at equal distances apart and parallel with the notched edge of the strip. After being treated thus the strip is 90 placed in a suitable bending machine and is bent upon itself to the section shown in Fig. 3, in which 4 is the lower member in which the apertures 1 are situated, said apertures serving for the passage of nails whereby to 95 attach the strip to the wooden rafters of the structure. 5 is a distance piece or back member bent up at right angles from the lower member 4; and 6 is the upper member of the strip which is bent forwardly at right angles 100 from the back member 5, said upper member 6 having the notches 2 along its edge at points above the nail apertures 1 in order to permit the nails to be reached by a hammer. The purlin is thus formed of a length 105 of metal of channel section whereof the lower member 4 bears on the wooden or other rafters. The equidistantly spaced slots 3 are disposed along or just below the line on which the member 6 is bent from the back or 110 distance piece 5. 7 is a rectangular plate or tile also of sheet iron, steel or other suitable

material which is stamped to shape and is provided as in my previous construction with a corrugation along each side edge. The portion of the material intervening between the two corrugations may be plane or it may be embossed as desired; and along its upper edge said plane portion is formed with an integral upstanding flange or "weather strip" 8 extending above the plane portion 7 of the tile for a distance equal to the height of the corrugations. The flange or "weather strip" 8 is provided integrally with a pair of tongues 9, 9, spaced the same distance apart as the slots 3 in the purlin, and the lower edge of the tile is formed with an extension or tongue 10.

In Fig. 6, 11 is one of the wooden rafters of a portion of a roof of a building and across these rafters the purlins are affixed by their lower members 4 being nailed thereto. The plates or tiles 7 are inserted in place by passing the tongues 9, 9, through the slots 3 and bending said tongues downwardly of the back or distance pieces 5. The lower edge of each plate or tile rests on the member 6 of the next purlin below, around which member the extension 10 is bent as seen clearly in Fig. 6. In this manner all the tiles are affixed to the purlins, either with the marginal corrugations in alignment downwardly of the structure or with said corrugations in staggered formation as shown in Fig. 5. It will be noticed that the distance separating the two members 4 and 6 of each strip is just sufficient to accommodate the upstanding flanges 8 of the tiles and that these flanges or "weather strips" 8 prevent access beneath the roof of any rain, dust or snow which may be driven up by the wind. Similarly the extensions 10 as in the previous constructions, prevent ingress of rain along the lower edges of the tiles. Furthermore these flanges 8 and the bent extensions 10 serve as bearing surfaces against the purlins 45 to secure the plates or tiles against lateral displacement by the wind, the flanges 8 resting firmly against the back or distance piece 5 of each purlin. Ample ventilation is secured by way of the laterally disposed corrugations. In this form of roofing or the like the plates or tiles interlock with the purlins so as to form a considerably stronger structure than heretofore, and the shape of the plates or tiles is such that considerably less material is required in their manufacture than was previously the case. The plates or tiles and purlins may serve equally well for the side walls of buildings as for the roofs, and said plates or tiles may be ornamented in any desired manner and may be protected from atmospheric changes or from reflecting the sun's rays by means of any desired coating or composition.

With the above described construction many facilities are afforded in the construction of a building. For instance ordinary ridging having joints may be entirely dispensed with, and instead two purlins may be placed back to back at the apex of the roof and a continuous strip of lead may be folded over same so that its edges take under the oppositely disposed upper members of the two purlins. Again, the structure is very simple to repair, for a single tile may be removed from within with great facility by simply straightening the tongues 9, 9, and allowing the damaged plate or tile to drop out, after which a fresh tile may be slid into place. By placing the slots 3 in the purlins at equal distances apart no difficulty is experienced in arranging the plates or tiles in staggered rows or otherwise as desired.

What I claim is:—

1. In a metallic roofing, the combination of upper and lower purlins of channel section arranged in spaced, parallel relation and having their lower side walls disposed against the roof rafters; and a row of metal tiles interposed between said purlins and housed at their upper ends in the space between the side walls of the upper purlin, each tile being formed at its upper end with an upstanding weather-stripping flange having a tongue engaged with the connecting wall of said upper purlin, and being formed at its lower end with an extension removably bent over the upper side wall of the lower purlin.

2. In a metallic roofing, the combination of upper and lower purlins of channel section arranged in spaced, parallel relation and having their lower side walls disposed against the roof rafters, the upper purlin being formed with a series of longitudinal slots at the junction of its upper side wall and connecting wall; and a row of metal tiles interposed between said purlins and housed at their upper ends in the space between the side walls of said upper purlin, each tile being formed at its upper end with an upstanding weather-stripping flange having its upper edge provided with a tongue which is inserted through the adjacent slot and bent downward against the connecting wall of the said upper purlin, and being formed at its lower end with an extension which is bent over the upper side wall of the lower purlin and inwardly against the under surface of such wall.

In testimony whereof I have hereunto set my hand in presence of two subscribing witnesses.

HEINRICH CHRISTIAAN FERRON.
